UNITED STATES PATENT OFFICE

CHESTER M. MACCHESNEY, OF CHICAGO, ILLINOIS, ASSIGNOR TO ACME STEEL COMPANY, OF CHICAGO, ILLINOIS, A CORPORATION OF ILLINOIS

DEVICE FOR USE IN LOADING CARS AND THE LIKE

Application filed October 17, 1929. Serial No. 400,196.

This invention relates to a device for use in loading freight cars and other carriers by the method described and claimed in United States Patent No. 1,703,495, granted February 26, 1929, on an application of Chester M. MacChesney and John Ekern Ott. The principal object of the present invention is to provide an improved form of stay for the flexible binders which are employed in the practice of that method for uniting a number of load elements to form a relatively large load unit having sufficient weight and frictional contact with the floor of the car or other carrier to retain itself substantially in place during transit, although otherwise free to move with respect to the car. According to one method of practicing the invention covered by said prior patent, the flexible straps or binders are arranged horizontally around the walls of the car before the load is placed in the car and are supported above the floor of the car by means of upwardly extending stays which are temporarily attached to the car walls by means of spikes formed preferably as integral parts of the stay so that after the required number of load elements have been arranged within the space enclosed by the flexible binders, the flexible binders may be drawn taut and secured around the load unit formed by the group of load elements with the result that the stays are automatically withdrawn from the car walls by the operation of tightening the straps or binders and move inwardly to the load so that the stays then support the encircling straps or binders against downward movement and the load unit, being preferably spaced from the car walls, is free to move as a unit under the influence of abnormal shocks although retained normally in place by reason of its weight and frictional contact with the car floor. The principal object of the present invention is to provide an improved form of supporting stay for the straps or binders which are arranged around the car walls so that the straps or binders may be detachably secured to the stays after the stays have been attached to the walls but are prevented from accidental detachment from the stays during the subsequent operation of forming the load unit and transporting the car with its load. Another object of the invention is to provide an improved metallic stay having means for detachably securing it to a car wall and embodying detachable means for securing an encircling strap or binder thereto. A further object of the invention is to provide an improved supporting stay of the kind described having one or more detachable spring clips which may be employed for securing one or more flexible binders thereto. Still another object of the invention is to provide a metallic stay having means for engaging the car wall and spacing the body portion of the stay therefrom so that portions of the detachable spring clip may be inserted through an opening in the stay into the space between the body of the stay and wall. Other objects relate to various features of construction and arrangement which will appear more fully herein-after.

The nature of the invention will be understood from the following specification taken with the accompanying drawings, in which certain embodiments of the invention are illustrated. In the drawings, Fig. 1 shows a perspective view of a portion of the inside of a railway freight car with flexible straps or binders supported around the walls of the car by means of the improved stay of the present invention and illustrating the partial formation of a load unit within the space around which the flexible binders are draped; Fig. 2 shows an enlarged elevation, looking toward the rear wall, of a portion of one of the stays with a flexible strap attached thereto; Fig. 3 shows an enlarged vertical section through the portion of the stay and strap illustrated in Fig. 2; Fig. 4 shows an enlarged detail section taken on the line 4-4 of Fig. 2; Fig. 5 shows a modified form of the detachable spring clip adapted to be employed with the stay illustrated in Figs. 1 to 4, inclusive; Fig. 6 shows a horizontal section similar to that of Fig. 4, illustrating a modified construction of the stay;

Fig. 7 is another horizontal section similar to that of Fig. 4, showing still another modification of the stay, and

Fig. 8 is another horizontal section similar to that of Fig. 4, showing still another embodiment of the invention.

In Fig. 1 of the drawings, there is illustrated a portion of a railway freight car 10 having a pair of side walls 11 and a connecting end wall 12, all of which extend upwardly from the floor 13. In the practice of the invention covered by the above mentioned United States patent, a relatively large load unit is preferably formed in each end of the car between the usual centrally located door openings and the end walls of the car and before placing the elements of each load unit in place within the car, the flexible binders which are subsequently employed in uniting these load elements into one compact load unit having the necessary weight and frictional contact with the floor, are draped around the walls of the car between the door openings and each end wall. These binders are preferably in the form of flexible steel straps 14 which are comparatively thin and of sufficient width and tensile strength to serve the purpose of uniting the load elements into the desired load unit. These straps are draped around the insides of the walls 11 and 12 and are supported above the floor 13 by means of vertical stays 15 which are also formed preferably of sheet metal and which have sufficient rigidity or stiffness to maintain substantially upright positions even after they have been detached from the car walls. In Fig. 1 of the drawings, the straps 14 which are to serve as binders for uniting the load elements to be arranged in the space between the door openings and one end wall of the car are shown arranged around this space and three barrels 16 are shown placed within this space adjacent the end wall but spaced slightly therefrom. A sufficient number of additional barrels are placed within this space to form a load unit of the desired size and weight when they are subsequently bound together by drawing the binders 14 taut around the barrels and uniting the ends thereof by seals or other fastening means, as more fully described in said prior patent.

The improved stay 15 is shown as a strip or bar of sheet metal having a central longitudinal web 15^a with a longitudinal rib or half-bead 15^b along each edge thereof. The beads or webs 15^b are adapted to impart sufficient stiffness or rigidity to the stay to cause it to maintain itself in the desired substantially upright position after being withdrawn from the car wall, while permitting the stay to conform throughout its length to the contour of the barrels 16 or other load units with which the stays contact when they are drawn inwardly from the car walls by the tighten-

ing of the binders 14. In addition, the ribs or beads 15^b serve the purpose of spacing the web 15^a outwardly from the car wall, it being understood that the stay is arranged within the car with the convex sides of the beads or ribs directed toward the surface of the car wall. The web 15^a of the stay has portions thereof cut out and bent inwardly at intervals to form inwardly directed sharpened spikes 15^c which are integrally formed with the web of the stay and which result in the formation of openings 15^d in the web conforming to the shape of the sharpened spikes. The sheet metal from which the stay is formed should be of sufficient stiffness to permit the spikes 15^c to be driven into the wood of the walls 11 and 12 without bending and when the desired number of stays 15 have been temporarily united with the car walls 11 and 12 by means of the spikes 15, the binders 14 are attached to the stays by means of the spring clips 17 which form a detachable part thereof. Each spring clip 17 comprises a body portion 17^a whose length measured vertically is substantially the same as the width of the strip or binder 14 and the part 17^a is integrally united with the inwardly bent inclined arms 17^b which diverge toward the car wall and which terminate in the inwardly directed reversely bent hooks 17^c. The web 15^a of the stay is provided at intervals, corresponding to the desired locations of the straps 14 above the car floor, with pairs of spaced openings 15^d and the openings of each pair are spaced apart so that they are adapted to be engaged by the arms 17^b of one of the spring clips 17. The metal of the web 15^a of the stay is bent inwardly at the adjacent edges of the two openings 15^d of each pair to form inwardly inclined diverging projections 15^e about which the hooks 17^c are adapted to engage when the spring clip has been placed in position. The arms 17^b of each spring clip are normally spaced apart to such an extent that when the clip is moved into engagement with the web of the stay opposite the position to be occupied by one of the straps 14, the inner curved surfaces of the hooks 17^c will lie opposite to and in engagement with the outer inclined surfaces of the projections 15^e. When the operator then pushes inwardly on the body portion 17^a of the spring clip, the arms 17^b will spread apart at their outer ends as permitted by the resiliency of the metal from which they are formed until the hooks 17^c snap over the projections 15^e and maintain an interlocking engagement therewith, as shown particularly in Fig. 3. Due to the engagement of the convex surfaces of the ribs or beads 15^b with the surface of the car wall, as shown in Fig. 4, there is provided a longitudinal channel 18 between the web of the stay and the adjacent surface of the car wall which accom-

modates the projections 15^t and the hooks 17^e of the spring clips.

Any desired number of spikes 15^e may be formed on each stay 15 but there should preferably be at least two spikes on each stay and the stays are of such length that their lower ends rest on the car floor both before and after the load unit is formed. The number of pairs of openings 15^e to be engaged by the spring clips 17 may vary according to the number of straps or binders 14 which are to be employed but in the embodiment of the invention illustrated in Figs. 1 to 4, inclusive, two pairs of openings 15^e are provided in each stay to accommodate two separate spring clips employed in securing the two binders 14 thereto. In the operation of loading the car, a sufficient number of stays 15 are placed in vertical positions and united with the car walls 11 and 12 by driving the spikes 15^e into the wooden inside sheathing of these walls. The straps 14 are then arranged around the space within the end of the car and are united with the stays by placing the spring clips 17 in position to straddle the straps and push them inwardly until the arms of each spring clip snap into engagement with the projections 15^t formed at the margins of one pair of openings 15^e. When the spring clip has thus been placed in position, an opening 19 is provided between the spring clip and the body of the stay which permits the engaging strap 14 to be moved longitudinally therethrough without disturbing the clip or the body portion of the stay. The flexible binders may thus be moved longitudinally with respect to the stays attached to the car wall and at the same time the present invention provides the advantage of permitting the straps to be secured to the stays without threading them through openings in the stays. When the desired number of barrels 16 or other load elements have been arranged within the space about which the straps 14 are arranged, the ends of the straps adjacent to the door openings, for example, are drawn inwardly and the straps or binders are stretched taut around the load unit by suitable strap stretching tools or other suitable means and then the overlapping ends of each strap or binder 14 are united by seals, spot welds or the like, to hold the load elements of that unit in compact, assembled relation. The number of barrels or other load elements forming one unit and the arrangement thereof within the car should preferably be such that the outer boundaries of the load unit when formed are spaced from the car walls 11 and 12 to permit such movement of the load unit's with respect to the car as may be occasioned by abnormal shocks during transit.

In Fig. 5 of the drawings there is illustrated a modified form of spring clip 20 which is formed from wire instead of sheet

metal and which comprises a body portion 20^a of the same length as the width of the strap and two diverging arms or end portions 20^b each of which terminates in a reversely bent and inwardly directed hook 20^c adapted to engage the projections 15^t shown in Fig. 3. The method of employing the spring clips shown in Fig. 5 is the same as that of using the spring clips 17, except that the openings 15^e are preferably of less width when the 75 clips 20 are employed so that lateral movement of the clips is prevented.

In Fig. 6 of the drawings there is illustrated a modified construction of the stay according to which the sheet metal stay 21 is provided with a body portion 21^a terminating at its edges in longitudinal curved flanges 21^b which are adapted to extend inwardly and contact edgewise with the surface of the car wall 22. The body portion 21 of this stay has spikes 21^c formed integrally therewith to engage the car wall and is provided with pairs of openings having inwardly extending projections 21^t adapted to be engaged by the arms of the spring clip 23 which is similar in construction to the spring clip 17 and which is adapted to secure in place one of the encircling straps or binders 24.

In Fig. 7 of the drawings there is illustrated still another modification of the invention according to which the metallic stay 25 has its central longitudinal web 25^a formed integrally with two longitudinal beads or ribs 25^b which have their convex surfaces directed outwardly and which have their edges arranged to contact with the surface of the car wall 26. This stay is provided with spikes 25^c adapted to be driven into the car wall and is further provided with pairs of 100 openings and cooperating projections 25^t which permit the spring clips 27 to be detachably secured thereto for maintaining in place a flexible strap or binder 28. The spring clip 27 and the method of attaching it to the stay 25 are the same as in the first form.

In Fig. 8 of the drawings there is illustrated still another modification in which the sheet metal stay 30 has a flat web 30^a provided at its edges with two inwardly curled beads 30^b which contact on their inner curved surfaces with the surface of the car wall 31. The web 30^a has spikes 30^c formed integrally therewith to engage the wall 31 and this web is further provided with pairs of openings 115 having inwardly extending projections 30^t at their edges to be engaged by the inwardly extending hooks of a spring clip 32 which, in this embodiment, has the form shown in Fig. 5. The spring clip 32 secures in place a flexible binder 33 similar to the flexible binders 14.

The stays embodying the present invention are preferably of sufficient stiffness to rest on the floor and support the binding straps after 130

the straps have been tightened around the load and the stays have been moved inwardly from the car walls, but the improved stays may be made flexible and suspended from the car walls in accordance with the method disclosed in United States Patent No. 1,726,709, granted September 3, 1929, on an application of Chester M. MacChesney and John Ekern Ott.

10. Although various forms of the improved stay have been illustrated and described in connection with the explanation of certain modes of using them, it will be understood that the invention may be constructed in various forms and may be employed in various ways within the scope of the appended claims.

I claim:

1. Apparatus for use in loading freight cars comprising a supporting rod having means for detachably engaging a car wall, and detachable means for attaching a binder to said rod.

2. Apparatus for use in loading freight cars comprising an upwardly extending supporting rod having means for attaching it to a car wall, and a detachable device for attaching a flexible binder to said rod.

3. Apparatus for use in loading freight cars comprising an upwardly extending rod having a spike extending therefrom, and a detachable device for attaching a binder to said rod.

4. Apparatus for use in loading freight cars comprising an upwardly extending supporting rod adapted to be detachably secured to a car wall, and detachable means for attaching a plurality of flexible binders in spaced relation on said rod.

40. 5. Apparatus for use in loading freight cars comprising a plurality of upwardly extending rods spaced apart and adapted to be secured to a car wall, and detachable devices for securing a flexible binder to each of said rods.

50. 6. Apparatus for use in loading freight cars comprising a supporting rod, means for securing said rod to a car wall, and a spring clip detachably engaging said rod for securing a flexible binder thereto.

55. 7. Apparatus for use in loading freight cars comprising a supporting rod adapted to be detachably secured to a car wall, and a spring clip having an interlocking engagement with said rod and adapted to support a flexible binder.

60. 8. Apparatus for use in loading freight cars comprising a supporting rod having a pair of apertures therein, and a spring clip adapted to support a flexible binder and having an interlocking detachable engagement with the walls of said apertures.

65. 9. Apparatus for use in loading freight cars comprising a supporting rod having a pair of spaced apertures and having in-

wardly inclined projections at the adjacent margins of said apertures, and a spring clip adapted to engage a flexible binder and having parts engaging said projections.

10. Apparatus for use in loading freight cars comprising a supporting rod having a pair of spaced apertures therein, and a spring clip adapted to straddle a flexible binder and having hooks adapted to be pressed into interlocking engagement with the edges of said apertures.

11. Apparatus for use in loading freight cars comprising a rod having a pair of apertures therein and having inwardly inclined projections at the adjacent edges of said apertures, and a spring clip adapted to straddle a flexible binder and having a pair of inwardly diverging arms terminating in hooks adapted to be spread apart when pressed against said projections and to interlock with said projections to hold said binder in predetermined position on said rod.

12. Apparatus for use in loading freight cars comprising an upwardly extending metal rod having longitudinal marginal portions adapted to engage a car wall and having a pair of apertures therethrough between said marginal portions, and a spring clip adapted to support a flexible binder and having parts extending into said apertures to form an interlocking engagement with said rod.

13. Apparatus for use in loading freight cars comprising an upwardly extending sheet metal rod having lateral inwardly extending parallel ribs adapted to engage the car wall, means for securing said rod to the wall, the body portion of said rod having a pair of spaced apertures therethrough between said ribs, and a spring clip adapted to straddle a flexible binder and having a pair of hooks engaging the edges of said apertures.

14. Apparatus for use in loading freight cars comprising a sheet metal rod having parallel longitudinal ribs adapted to engage the car wall and to space the intervening body portion from said wall, a spike formed integrally with said rod between said ribs for securing said rod to said wall, said rod having a pair of apertures therethrough spaced apart vertically, and a spring clip having diverging arms provided with hooks adapted to interlock with said rod at the edges of said apertures.

In testimony whereof, I have subscribed my name.

CHESTER M. MACCHESNEY.
